CLAIM

The ornamental design for a chicken toy, as shown and described.

DESCRIPTION

FIG. 1 is a perspective view of a chicken toy showing my new design.

FIG. 2 is a second perspective view of the chicken toy of FIG. 1.

FIG. 3 is a front view of the chicken toy of FIG. 1.

FIG. 4 is a rear view of the chicken toy of FIG. 1.

FIG. 5 is a side view of the chicken toy of FIG. 1.

FIG. 6 is an opposite side view of the chicken toy of FIG. 1.

FIG. 7 is a top of the chicken toy of FIG. 1.

FIG. 8 is a bottom view of the chicken toy of FIG. 1.

FIG. 9 is a third perspective view of the chicken toy of FIG. 1 in an alternate use state; and,

FIG. 10 is an exploded view of the chicken toy of FIG. 1 in a second alternate use state.

The broken lines shown in the drawings depict portions of the chicken toy that form no part of the claimed design.

1 Claim, 10 Drawing Sheets
